US0D1100193S

(12) **United States Design Patent** (10) Patent No.: **US D1,100,193 S**
(45) Date of Patent: ** Oct. 28, 2025

(54) **INJECTION MONITORING ADDON FOR ATTACHMENT TO AND MONITORING OF AN INJECTION PEN**

(71) Applicant: **BIOCOP PRODUCTION S.A. A CONSEIL D'ADMINISTRATION, Issoire (FR)**

(72) Inventor: **Alain Marcoz**, Montmorin (FR)

(**) Term: **15 Years**

(21) Appl. No.: **35/519,390**

(22) Filed: **Nov. 28, 2023**

(80) **Hague Agreement Data**

Int. Filing Date: **Nov. 28, 2023**

CLAIM

The ornamental design for an injection monitoring addon for attachment to and monitoring of an injection pen as shown and described.

DESCRIPTION

1. Injection monitoring add-on for attachment to, and monitoring of, an injection pen

1.1 : Perspective

1.2 : Top

1.3 : Bottom

1.4 : Front

1.5 : Back

1.6 : Left

1.7 : Right

Injection monitoring add-on for attachment to, and monitoring of, an injection pen.

(Continued)

The broken lines illustrate portions of the injection monitoring add-on for attachment to and monitoring of an injection pen that form no part of the claimed design.

1 Claim, 7 Drawing Sheets
